UNITED STATES PATENT OFFICE.

FRANK KAGERMEIER, OF NEW ULM, MINNESOTA.

CONCRETE BUILDING BLOCK.

Application filed May 8, 1922. Serial No. 559,155.

To all whom it may concern:

Be it known that I, FRANK KAGERMEIER, a citizen of the United States, residing at New Ulm, in the county of Brown and State 5 of Minnesota, have invented certain new and useful Improvements in Concrete Building Blocks; and I do hereby declare the following to be a full, clear, and exact description of the invention, such as will 10 enable others skilled in the art to which it appertains to make and use the same.

This invention relates to a building structure, and particularly to a building block especially adapted for forming a wall.

15 It is an object of this invention to provide a building block which can be easily and inexpensively made and very efficiently used in forming a wall.

It is a further object of the invention to 20 provide such a block having recesses forming locking means for the adjacent blocks and also having a longitudinal channel in one side affording an air space in the wall.

It is still another object of the invention 25 to provide a special lock adapted to be used to form a corner of the wall.

These and other objects and advantages 30 of the invention will be fully set forth from the following description made in connection with the accompanying drawings in which like reference characters refer to the same parts throughout the different views, and in which—

Fig. 1 is a plan view of a wall having a 35 corner therein using the block of this invention;

Fig. 2 is a vertical section on the line 2—2 of Fig. 1;

Fig. 3 is a partial plan view of the wall; 40 Fig. 4 is a view in side elevation of a portion of the wall; and

Fig. 5 is a perspective view of a modified form of block.

Referring to the drawings, it will be seen 45 that the wall illustrated in Fig. 1 is formed of separate blocks 1 of general rectangular shape or forming a parallelopiped having one exterior plane vertical surface 1^a. On the opposite vertical surface which is the 50 inner surface of the block is formed a dove-tailed groove 1^b. This groove at its longest dimension is substantially one-half the length of the block and twice the horizontal width of the block. It will be seen that this 55 dove-tailed groove forms projections at each side thereof on the inner surface of the

block and the block is, furthermore, provided with a vertical recess 1^d at its inner corners which is illustrated as being substantially a quadrant of a cylinder. The 60 blocks are also provided on their inner surfaces with a longitudinally extending channel 1^c disposed between the top and bottom surfaces thereof and shown as being substantially central of the block.

65 The blocks are laid to form a wall, as illustrated in Fig. 1, in two longitudinally extending series, or courses, the projections at each side of the dove-tailed groove fitting into the groove on the block in the same horizontal course, the recesses at the corners of the blocks falling adjacent each other to form a substantially semi-cylindrical recess. The channels 1^c also come adjacent 70 each other and form a longitudinally extending enclosed air space for each course of the wall communicating with each other to form a channel extending longitudinally centrally of the wall.

75 In order to form a corner of the wall, a block 2 is used similar to the block 1 but having a recess 1^d omitted at one corner. A special block 3 is also used similar to the block 1 except that the recess 1^d is omitted at one corner and a projection 3^a is formed 80 on its end surface which corresponds to the projection at the inner side of the block 1 at one side of the dove-tailed groove 1^b. A third special block 4 is formed which is the same as one-half of the block 1 when the 85 same is divided by a central vertical plane midway of its length. The disposition of the special blocks is clear from the showing in Fig. 1 and it will be seen that the longitudinal channels 1^c in the block co-operate to 90 continue the enclosed air space in each course around the corner of the wall. The successive courses of the blocks will have their vertical joints staggered or offset, as 95 illustrated in Fig. 4. The top course of the wall, if the same is used for a wall having an exposed top surface, will be formed of blocks 5 in which the recesses 1^d are omitted so that the top of the wall will be an entirely 100 plain tight surface.

105 In Fig. 5, a modified block 6 is shown which has only triangular projections extending inwardly from the bottom of the longitudinal channel therein.

110 From the above description it is seen that applicant has provided a simple and efficient block which can be quickly assembled to form

a strong, compact and interlocked wall having a desirable air space therein. By a slight variation, the block can be modified to form the corner of the wall without changing the thickness or general formation of said wall. The wall will, of course, be bound with mortar. The recesses 1⁴ afford communication vertically between the various horizontal air spaces in the different courses, which is a desirable feature. The block can be made of concrete cement or any suitable or similar material.

It will, of course, be understood that various changes may be made in the form, details and proportions of the block without departing from the scope of applicant's invention, which, generally stated, consists in the matter shown and described and set forth in the appended claims.

20 What is claimed is:

1. A wall structure comprising two adjacent series of superposed courses each course formed of blocks having plane outer surfaces, the adjacent blocks of said courses having interlocking dove-tailed grooves and projections respectively on their adjacent surfaces and having longitudinally extending channels therein between their top and bottom surfaces whereby a central air space is formed between the two horizontally adjacent courses.

2. A corner wall structure formed of adjacent series of superposed courses of blocks, said blocks having smooth outer surfaces and the blocks of horizontal adjacent courses having interlocking tongues and grooves on their adjacent surfaces, said tongues being

substantially the horizontal width of the blocks, said series extending at right angles to each other, one of the inner corner blocks having a locking tongue projecting from its end surface and co-operating with the groove in the block extending at right angles to its end and a filling block at the corner of half the length of the other blocks.

3. A building block comprising a rectangular block having a vertically extending dove-tailed slot centrally disposed on its inner surface and extending throughout the same, the longest dimension of which is substantially half the length of the block, said blocks also having a channel extending centrally longitudinally of the block on said said inner surface throughout the length of the block and deeper than said slot.

4. A building block of general rectangular shape having a vertically extending dovetailed groove on its inner surface, a central longitudinal channel in said surface and vertically extending channels at its inner corners.

5. A wall formed of a plurality of complementary building blocks arranged in two longitudinally extending series, said blocks comprising parallelopipeds having vertically extended interlocking dove-tailed recesses and tongues, respectively, in their adjacent surfaces, longitudinally extending channels in said surfaces forming a longitudinal channel in said wall, and vertically extending mating channels at their inner corners.

In testimony whereof I affix my signature.

FRANK KAGERMEIER.
